MINERAL WOOL BAT COMPRESSOR AND COOLER

Thomas F. Mooney, New Lexington, Ohio, assignor to Ludowici-Celadon Company, Chicago, Ill., a corporation of Illinois

Application November 17, 1939, Serial No. 304,920

10 Claims. (Cl. 154—27)

The invention pertains to the manufacture of insulating units or bats of mineral wool or the like, although in certain phases it has adaptability to other uses. Considered with greater particularity, the invention includes an apparatus by which slabs or blocks of resilient mineral fibers may be formed into resilient light weight bats of substantially uniform predetermined dimensions and shape.

In the manufacture of mineral wool, the slag, after being melted and while molten, is blown by a high velocity jet of air or steam to form filamentary threads or fibers. The fibers or filaments are blown into a settling or receiving chamber and therein settle upon a traveling conveyor by which the resultant mat or blanket is withdrawn from the chamber. For various reasons, it is desirable to apply a binder or cementitious substance to the fibers when the latter are to be used in the manufacture of batting sheets and for certain other purposes, and this application may and, preferably, is made at the time the fibers are in the state of formation and in a dispersed condition within the forming and settling chamber. One practice is to spray the binder upon the fibers as they are being formed and to create, within the chamber, what may be termed an "atmosphere" of binder substantially in a vapor form so that the individual fibers are coated with binder to a substantial extent, the fibers thereby tending to stick together and to agglomerate into a relatively flocculent although somewhat uneven layer or sheet upon the conveyor. The mat or blanket thus produced is compressed by pressure rolls to substantially the desired thickness of the ultimate bats.

Because the binder coated fibers tend to accumulate unevenly, that is, in bunches or in different quantities, as respects density or thickness, over adjacent parts or areas of the conveyor, and because of the resiliency of the fibers which cause them to spring back after rolling before the binder has set, the mat or blanket even after subjection to the compression of presser rolls will be uneven in cross-section or thickness dimension as between different portions or areas of the sheet. This variation in thickness makes for difficulties in handling, packaging and using the bats which are cut from the blanket coming from the chamber.

It becomes, therefore, one of the primary objects of the invention to provide bats of mineral wool which will present relatively smooth, major

surfaces and will be of substantially uniform thickness.

Still another object is to provide a machine adapted to carry out rapid production of the bats in an economical and expeditious fashion.

Many other objects as well as the advantages of the invention will become apparent and will be understood as the description is read and as the drawings are studied. In the drawings:

Fig. 1 is a somewhat diagrammatic end elevation of a preferred form of a bat cooler embodying the invention and adapted to carry out certain steps in the process thereof;

Fig. 2 is a fragmentary sectional view, taken along the line 2—2 of Fig. 1;

Fig. 3 taken along section line 3—3 of Fig. 5 is a detail view in section of a portion of a cooler tray and its associated compression or clamping plate and illustrating an adjustable hinge or pivot for the plate;

Fig. 4 is a side elevation of the cooler as viewed from a position to the right of Fig. 1, the scale of drawing being somewhat greater than that of Fig. 1;

Fig. 5 is a top plan view of an end edge portion of one of the compression or clamping plates together with an associated structural part of the machine frame illustrating a releasable latch mechanism and a latch operating trigger cooperative with the latch whereby the compression plate and tray proper may be moved relatively toward and from one another and secured in clamping or released positions;

Fig. 6 is a detail view in end elevation of the releasable latch in its position when the clamping plate and tray are in clamping position but about to strike a fixed trigger which will open the latch and permit the compression plate to drop away from the tray to release the bats;

Fig. 7 is a detail view in side elevation, with some parts in section, of the latch and the associated release trigger as viewed from line 7—7 of Fig. 6; and

Fig. 8 is a detail view of the ends of a tray and its associated plate showing their relationship to the conveyor mechanism by which they are carried and also illustrating one arrangement whereby the plate and tray may be adjusted for the production of bats or units of various thicknesses.

The cooler illustrated is designed to receive the bats produced from the compressed mat or blanket by cutting it longitudinally into strips and then transversely into bat lengths of the requisite dimensions. The mineral wool, at the time it

emerges from the chamber, is still quite hot, and the binder applied to the fibers is tacky but adapted to set or harden as it cools. Consequently, the wool must be cooled down and the binder must set before the units or bats may be packaged. The cooler illustrated receives the mineral wool bats and serves to compress them to a predetermined thickness and to hold them to such thickness while they are being cooled and the binder is setting. When the bats are discharged from the cooler, they may be immediately packaged and will be of permanent dimensions.

Any suitable supporting frame members as standards or columns 2 and 3, adequately braced and supported on a base plate 4 in turn resting upon a flooring, carry shaft bearing hangers 5 and 6 which support a driven shaft 7 and a drive shaft 8, the shaft 8 being driven, in turn, by any power mechanism. Shaft 7 carries a pair of sprocket wheels 9 secured thereto, one at each end adjacent to the shaft bearings in hangers 5 and, similarly, shaft 8 carries a pair of sprocket wheels 11, the sprockets at corresponding ends of the two shafts being aligned with one another and all being of the same diameter. Chains 12 are trained over the aligned pairs of sprockets and the sprockets on each shaft have their teeth in registration, that is, at corresponding radial positions with respect to the axis of the shaft to which they are related for the purpose of aligning with similar chain links to which the opposite ends of bat carrier trays 13 are secured. Each tray may be composed of a flat metal sheet bounded by angle irons 13' to which the metal sheet may be riveted, welded or otherwise secured.

Each of the several trays 13 of which there may be any desired number dependent upon the rate of operations and other factors including the rate of bat cooling, is secured at its ends to similar and correspondingly opposite links of the conveyor chains and in such manner that it is substantially perpendicular to the direction of travel of the chains and horizontal during those portions of its travel which are tangential to the sprockets. The trays in the illustrated embodiment, are rigidly secured to the chain links and at places substantially midway between their front and rear edges thereby the better to balance the load upon the chains, and, as will be observed in Fig. 1, each is inverted in its travel from a position at the left of said figure to a position at the right thereof, the chain traveling in a clockwise direction to the observer. In Fig. 1, S₁ designates the tray loading station at which place the bats are placed upon the trays as they come into position and S₂ designates the unloading station at which place the bats are unloaded for packaging or other purposes.

Associated with each tray is what may be termed a compression or clamping plate 14, corresponding in construction including angle irons 14' and in overall dimensions with each tray and adapted to cooperate therewith to clamp and, to a degree, compress a series of bats therebetween. Figs. 3, 6 and 8 show the detailed construction of the trays and clamping plates.

Rigidly secured at the rear edge of each end of each clamp plate and at right angles to the plane of the clamp plate is one end of an arm 15 which at its other end is hinged to the tray with which it is associated by hinge pins 16 selectively disposable through any of a series of circular apertures 17 formed in spaced relation to one another through the said other end of arm 15. As will be

observed in Fig. 3, each pin 16 is arranged to be easily retracted from any aperture 17 for disposal through another and to such end is slidably mounted in a tubular housing 18 secured to the tray angle iron 13'. Each housing 18 is provided with a cap 19 between the inner side of which and a collar 21 secured to the hinge pin, a coiled spring 22 abuts. The spring, therefore, normally tends to thrust the beveled end of the pin through registering apertures in angle iron 13' and one end of a strap iron member 23 welded or otherwise secured to the outer side of the tray angle iron 13' and also through whichever one of apertures 17 is aligned therewith. A key pin 24 driven through a hole in the outer end of each hinge pin 16 provides a handle by which to retract the hinge pin. In this manner each clamp plate 14 is pivotally connected with its associated tray and may be swung toward and from the same to clamp or release the interposed bats.

A releasable latch mechanism by means of which the front end of each clamp plate may be secured to its associated tray and at a predetermined distance therefrom, is illustrated in detail in Figs. 5, 6, 7 and 8. The strap iron members 23, above mentioned, one of which is secured to each end of a tray and each of which is offset outwardly at its rear end to provide a recess for free swinging movements of the arms 15, are also offset outwardly across the connection between the tray and the chain link to which it is attached as indicated at 25, and are also offset outwardly as at 26 slidably to receive and to retain a latch bar 27. Each latch bar in the forward edge of its end to be connected with a tray, is provided with a plurality of spaced notches 28 selectively to receive and engage a fixed pivot provided by a cylindrical spacer or collar 29 which is disposed about a bolt 31 extending through and rigidly secured to the offset portion 26 of the strap iron 23 and the angle iron 13'. The collar 29 not only serves as a pivot about which the latch arm 27 may rock, but also as a spacer between the offset portion 26 of the strap iron and the angle iron 13' so that the bolt 31 may not be tightened to the point of binding the latch arm 27. Rearward of each latch arm and firmly secured to the angle iron 13' at opposite ends of each tray is a piece of strap iron 32 which is suitably notched in its forward edge to position and retain one end of a coil spring 33, the other end of which abuts against the latch arm 27, the rear edge of the arm 27 being suitably notched to position and retain the forward end of the spring.

The springs 33 normally urge the latch arms 27 forwardly thereby to retain the pivot 31 in whichever notch 28 it has been disposed and likewise to urge the upper or free end of each latch outwardly. At suitable distances from the notches 28 each latch arm is also notched along its front edge as indicated at 34 and 35 for the reception of a cylindrical spacer collar 36 disposed about a bolt 37 extending through and secured to the angle iron 14' and the offset portion 38 of a piece of strap iron welded or secured to the angle iron 14' at the adjacent end of the clamp plate.

It will now be apparent that each clamp plate may be adjustably hinged to its associated tray at any of several vertical distances between the tray surface and the clamp plate surface and that since the notches 28 are disposed at intervals spaced equally (in the present embodiment)

with the spacing between the centers of the apertures 17, the front end of each clamp plate may be spaced at a perpendicular distance from the front end of its associated tray equal to the perpendicular spacing between the rear ends of the clamp plate and tray. In other words each clamp plate and tray may have their surfaces parallel to one another or they may be arranged at other predetermined angles with respect to one another if desired. When the bolt 31 is engaged in latch notch 34 the clamp plate is secured relative to its associated tray and this position will be referred to as the bat clamping or compression position. When the bolt 31 is disposed in latch notch 35, the outer edges of the clamp plate and tray are held in widely spaced relationship for the reception of bats at station S' or the discharge of bats at station S₂.

The swinging movements of the clamping plates toward and from their associated trays are controlled purely by gravity when the latch mechanism is released. This action is best illustrated in Fig. 1 wherein the travel of the conveyor is clockwise as indicated by the long arrows. As each tray with its associated clamp rises toward loading position S₁ the bolt 31 is engaged in latch notch 35 so that the tray and clamp plate are securely held in open position. When loading station S₁ is reached, the operator or appropriate feed mechanism places a series of bats upon the upper surface of the tray and, as the tray progresses in its upward movement, triggers 39 engage the latches carried by such tray and release the latches from engagement with bolts 31 so that the clamp plate under the action of gravity drops to a position where the springs 33 force the bolts 31 to engage in notches 34 thereby to secure the clamp plates in bat clamping and compressing relationship with respect to the tray.

The conveyor moves the trays on an upward course and about the axis of the upper sprocket shaft and thence on a downward course to the unloading station or position S₂, the trays and clamp plates and the bats or batting sheets between them being inverted enroute. Just before the trays reach the unloading station S₂ the latches engage triggers 41 which move the latches so as to disengage the bolts 31 from the notches 34 and the clamp plates drop under the action of gravity to the open position as indicated at station S₂ in Fig. 1 and in dotted lines in Fig. 8. As each clamp plate drops to open position the springs 33 are first compressed and then, when the triggers clear, they return the latch arms to positions where the bolts 31 engage in notches 35, and the parts are held thus in open position through the return movement of the trays and clamp plates from station S₂ to station S₁. The details of the latch release mechanism will now be described.

Extending horizontally across the ends of columns 2 and 3 and rigidly secured thereto in any suitable manner, are channel members 42 on the outer ends of which the latch release triggers 39 and 41 are mounted at an angle to intercept the latch arms. In order to bring the triggers 39 and 41 into the path of roller strikers 43 which project laterally from and are secured to the free ends of the latch arms 27, the channel members 42 being disposed well away from the conveyor to provide the necessary clearance therefrom, the triggers 39 and 41 are mounted on long bolts 44 which pass through them through holes in a bar 45 disposed transversely across the channel

member 42 and through the bottom of the channel member. Cylindrical spacers 46 disposed over the bolts and between the triggers and bars 45 serve to position the triggers at the desired place for engagement with the roller strikers 43 carried by the latch arms. When a loaded tray, in moving away from the loading position S₁, reaches the point where the roller strikers 43 engage with the inclined triggers 39, continued movement of the conveyor on the upward course of its travel will cause the latch arms to be moved about their pivots 31 thereby disengaging the bolts 31 from the notches 35. Similarly, when the roller strikers 43 engage the triggers 41, the continued movement of the conveyor on its downward course and toward the unloading station will withdraw the bolts 31 from the notches 34 with which they have been engaged.

When the bats are loaded onto the trays of the conveyor, they are still quite warm, if not hot, and all or sufficient of the binder with which the fibers have been coated is still tacky enough to become attached to the fibers it touches under the compression effected by the clamp plate. The conveyor may be driven from any suitable source of power by a steady movement or it may be operated intermittently as may be preferred, but in any case, the timing preferably is arranged so that between the time the bat leaves the loading station S₁ and the time it arrives at the unloading station S₂ it will have been cooled to a sufficient extent by the surrounding atmosphere to cause the binder to set at least to the point where the bats will hold the shape and dimension to which they have been pressed. The trays and the clamp plates preferably are made of heat conducting material so as to conduct and dissipate the heat contained in the bats and the weight of each of the clamp plates is sufficient to compress at least the irregular upper surface portion of the bats to an even surface and to provide a predetermined thickness of bat even though the density of the bats may vary somewhat between different portions thereof. When the binder has set and the bats have cooled, they retain their predetermined shape and dimensions and are ready for packaging. Unlimited quantities of bats of substantially identical shape and dimensions may be manufactured very easily and economically, and it is a simple matter to manufacture the sheets or bats in any desired size.

Obviously, the invention is susceptible of many adaptations and variations, and, as respects certain features, is susceptible of embodiment in other forms differing widely from the embodiment chosen for illustration herein. Consequently, it is desired that the invention be limited only by its spirit and the scope of the appended claims.

60 I claim:

1. In an apparatus for producing light-weight, binder-treated mineral wool bats of predetermined thickness, the combination of an endless carrier, a series of trays fixedly mounted thereon and adapted to receive a plurality of partially cooled bats, a compression plate pivotally connected at one edge with each of said trays, the free edge of each plate being gravity actuated toward its respective tray upon the upward travel of the tray and away from such tray upon the downward travel thereof, means for locking said plate in open and closed position with respect to said tray, means for releasing said locking means upon downward travel of the tray to

permit the discharge of the bats therefrom, and means for releasing said locking means upon upward travel of the tray to permit the gravity-induced compressing action of said plate.

2. In a machine of the character described, a conveyor mechanism having a closed path of travel including an upward course against gravity to a loading station and a downward course with gravity to an unloading station, a tray carried by said mechanism and arranged to lie in a substantially horizontal plane at the loading station, a compression plate carried by said mechanism adjacent to said tray and normally tending to move relatively toward said tray under the influence of gravity when on said upward course for cooperation with said tray to clamp mineral wool therebetween and normally tending to move relatively away from said tray under the influence of gravity when on said downward course for releasing said wool, latch means for securing said plate and tray in clamping and released relationships during predetermined space intervals, and latch operating means operative upon predetermined movement of said tray for releasing said latch means to permit gravity to move said plate alternately into clamping and releasing relationship with said tray.

3. In a machine of the character described, a conveyor mechanism having a closed path of travel including an upward course against gravity to a loading station and a downward course with gravity to an unloading station, a tray carried by said mechanism and arranged to lie in a substantially horizontal plane at the loading station, a compression plate carried by said mechanism adjacent to said tray and normally tending to move relatively toward said tray under the influence of gravity when on said upward course for cooperation with said tray to clamp a plurality of bats therebetween and normally tending to move relatively away from said tray under the influence of gravity when on said downward course for releasing the bats, latch means for securing said plate and tray in clamping and released relationships during predetermined space intervals, latch operating means operative upon predetermined movement of said tray from said loading station for releasing said latch means to permit gravity to move said plate and tray relatively into clamping relation, and latch operating means operative upon predetermined further movement of said tray for releasing the latch to release said tray and plate from clamping relation thereby to permit gravity to move said plate relatively away from said tray on said downward course.

4. In a machine of the character described, a conveyor mechanism having a closed path of travel including an upward course against gravity past a loading station and a downward course with gravity past an unloading station, a tray carried by said mechanism and arranged to lie in a substantially horizontal plane at each of such stations, a compression plate carried by said mechanism adjacent to said tray and normally tending to move relatively toward said tray under the influence of gravity when on said upward course for cooperation with said tray to clamp bats therebetween and normally tending to move relatively away from said tray under the influence of gravity when on said downward course for releasing the bats, latch means for securing said plate and tray in clamping and released relationships, and means operative at predetermined positions of said tray in its travel for re-

leasing said latch means to permit gravity actuation of said plate alternately into clamping and releasing positions.

5. In a machine of the character described, a tray adapted to receive bats thereupon, conveyor means for moving said tray from a loading to an unloading station and for inverting said tray between said stations, a plate associated with said tray and cooperative therewith for clamping bats therebetween, said plate and tray being relatively movable toward and from one another under the influence of gravity, means for releasably securing said plate and tray in relative positions a sufficient distance apart for the free reception of bats therebetween and in relative positions at a lesser distance apart for clamping the bats, means operative upon predetermined movement of said tray and plate from said loading station toward said unloading station for releasing said securing means to permit gravity to move said plate and tray relatively toward one another from the first said secured positions into the second said secured positions, and means operative upon inversion of said tray for releasing said securing means to permit gravity to move said plate and tray relatively away from one another from the second said secured positions into the first said secured positions for removal of the bats at said unloading station.

6. A machine for the manufacture of insulating bats of predetermined thicknesses from a fibrous binder treated material, comprising an endless conveyor, a plurality of trays carried by said conveyor and movable therewith between a loading station and an unloading station, each of said trays when at said loading station including a relatively fixed lower member and an upper member movable toward the lower member under the influence of gravity to compress and clamp a quantity of said material between the members when the members are at said loading station, said movable member being adapted to move away from said fixed member under the influence of gravity at said unloading station to release the material, latch means adapted to hold said members apart for loading at said loading station and for securing said members in material clamping relationship when said tray leaves its loading station, means operative upon movement of a tray from said loading station for releasing said latch means so that said members may be clamp said material, and means operative upon movement of the tray to a place adjacent to said unloading station for releasing said latch means to release said members from clamping engagement with the material.

7. In a machine of the character described, the combination of an endless conveyor, a series of trays fixedly mounted thereon, a gravity actuated compression plate pivotally mounted in cooperative relation with each of said trays, said plates being gravity actuated toward their respective trays upon the uptravelling lap of the conveyor and gravity actuated away from said trays upon the downtravelling lap of the conveyor, a latch comprising cooperating elements carried by each tray and plate, each latch being constructed to releasably latch the plate in both open and closed position with respect to its companion tray, stationary means in proximity to the upward path of travel of the trays for successively releasing said latches to permit the plates to close to a predetermined position with respect to their trays, in which closed position the trays are automatically secured by

said latches, and means in proximity to the downward travel of said trays for releasing the latches to permit the trays to assume an open position under the influence of gravity, in which position the trays are automatically secured by said latches.

8. In an apparatus of the character described, the combination of an endless conveyor, a series of trays fixedly mounted thereon, a compression plate pivotally mounted on the conveyor adjacent to each tray, said plates being movable by gravity on their pivots toward and away from their respective trays at loading and unloading stations, respectively, a latch for each tray comprising cooperating elements carried by the tray and plate whereby the plate is automatically locked in open position and in closed position, stationary means for successively releasing said latches to permit gravity actuated closing movement of the trays at the loading station, and stationary means for successively releasing said latches to permit gravity actuated opening movement of said trays at the unloading station.

9. In a machine of the character described, a tray, means for moving said tray progressively past a loading and an unloading station, a plate pivotally connected to said tray so that the free edge thereof may be gravity actuated toward and away from said tray at the loading and unloading stations, respectively, means for releasably holding said plate in closed and in open relation to the tray, means operative upon predetermined movement of said tray and plate from said loading station toward said unloading

station for releasing said holding means to permit gravity actuation of said plate to closed position, and means for subsequently releasing said holding means to permit gravity actuation of said plate to open position at the unloading station.

10. A machine for the manufacture of bats of predetermined thicknesses from mineral wool having a binder applied thereto comprising conveyor means movable progressively past a loading station and an unloading station, a plurality of trays mounted upon said conveyor means in spaced relation to one another, a plate associated with each tray and cooperative therewith for clamping bats therebetween, each said plate and its associated tray being relatively movable toward and from one another under the influence of gravity, a latch arm pivotally connected with each tray and variably connectible to the companion associated plate for releasably securing such trays and plates in relative positions a sufficient distance apart for the relatively free reception of bats therebetween and in positions relatively closer together for clamping bats between them, and means effective upon movement of each tray from said loading station for releasing said securing means to permit gravity to move such tray and its associated plate relatively toward one another from receiving to clamping position, and means for subsequently releasing said securing means to permit gravity separation of such tray and plate for unloading purposes.

THOMAS F. MOONEY.
